UNITED STATES PATENT OFFICE

2,445,104

FUEL CARBURETING MEANS

Charles M. Colvin, Wilmette, Ill.; John L. Corliss, executor of said Charles Colvin, deceased, assignor to Nellie M. Satterfield, Lexington, Ohio

Application Sept. 15, 1944, Serial No. 554,213

1 Claim. (Cl. 251—34)

1

My present invention, as described in the following specifications, and illustrated in the accompanying drawings, relates to means for mixing oil and air in suitable proportions, to provide the best combustion fuel for heating furnaces, internal combustion engines and the like.

One of the objects of my present invention is to provide a means for mixing oil and air for combustion fuel, and means for quickly and readily adjusting the proportions of the mixture to provide the best fuel as various grades of oil are employed.

Another object is to provide a means for adjusting and supplying the air in the desired proportion, without the use of needle-valves, or other valves liable to clog and interfere with the proper mixture.

With the above, and other objects in view, which will more fully appear from the following specification, I have described herein and illustrated one embodiment of my invention, adapted to supply mixed oil and air to heating furnaces.

In the accompanying drawings,

Fig. 1 is a front elevation of my device, having portions broken away to show some internal parts.

Fig. 2 is a section detail view of certain of the parts forming the device.

Fig. 3 is a cross-sectional view through the member 8 taken on line 3—3 of Fig. 2.

In the accompanying drawings, 1 represents any suitable base upon which to mount the parts shown as mounted thereon. This base may be supported by legs, as 2, 2. In this base I have provided a suitable oil tank or sump 3, 3 for holding a quantity of oil conveniently for use in the device. This oil tank 3 is connected by means of a pipe 4 with any suitable storage tank (not shown) for supplying oil to the tank 3. A float-valve of any usual construction 5 is provided to maintain the level of oil in tank 3 at the desired level. The top of tank 3 is closed by a plate as 21 on which may be mounted the pump or blower 7. Mounted upon the base 1, is an electric motor as 6, of any usual type, and preferably directed connected to the pump 7. Connected to the vacuum side of the pump is the air intake tube 8. A suitable pipe 9 extends from the oil tank 3 to the air intake tube 8, as shown, for the purpose of supplying oil from the oil tank to the vacuum side of the pump, when the device is in operation, as hereinafter described. A suitable screen or strainer as 10 is provided at the lower end of the pipe 9 to prevent foreign objects from entering the pipe and causing difficulties in the

2

operation of the other parts. Near the upper end of the air intake tube 8 I have provided openings as 11, 11 to permit air to enter the air tube. At a suitable location in the air intake tube I have provided a disk 12, with a central opening 13 therein. This closes the air intake tube so that air may not pass downward through it excepting through this central opening. A tube 16 is provided to close this opening 13, and adapted to be moved up and down therein, as hereinafter described. This tube 16 is provided with a slot as 15, extending above and below the disk 12, providing an opening above the disk 12 through which air may enter, and pass downward into the air tube 8. The upper end of the tube 16 is attached to the underside of the screw cap 17, as shown. This cap in turn, forms a closure for the upper end of the air intake tube 8. The cap 17 is threaded internally and adapted to screw on the threaded upper end of the air intake tube 8. A suitable pipe as 18 is provided, to carry the mixture of air and oil from the compression side of the pump to the furnace and oil burner (not shown). 20 is any convenient gauge for observation showing the pressure maintained in the pump.

The operation of my device is as follows: The motor is started, and this operates the pump. The pump sucks air in through the air intake openings 11, and through the slot 15 above the disk 12, and delivers it through the slot and lower end of tube 16 into the air intake tube 8 below the disk 12. The suction of the pump also draws oil up from the oil tank 3 through the pipe 9 into the air intake tube 8. The oil and air thus delivered to the intake tube 8 is drawn through the pump, and the action of the pump suitably mixes it, and blows it on through the pipe 18 to the burner in the furnace (not shown). To regulate the mixture of air and oil, the cap 17 is screwed upward, or downward, as required. The higher the cap is raised, the more of the slot 15 is exposed above the disk 12, permitting more air to pass downward to the air intake tube 8. To reduce the supply of air, the cap 17 is screwed downward, reducing the length of the slot 15 exposed above the disk 12, thereby reducing the flow of air through it to the air intake tube 8.

By this construction I have supplied a simple, reliable and inexpensive device for mixing air and oil and feeding it to a furnace. There is but one moving part, which is easily operated, and cannot possibly get clogged up or out of order. I have dispensed with all needle valves and other unreliable valves which become clogged and stick

3

in position. While I have shown the opening 14 as a slot, it could be some other shape, if desired, so long as it supplied air from above the disk 12 to below it as in the present construction.

While I have shown my device as designed for use in mixing air and oil to supply fuel for a heating furnace, it will be apparent that it could be used equally as well in connection with the fuel supply for an internal combustion engine and to otherwise mix and supply air and gas, or two separate gases, if desired.

While I have shown the construction which I consider best adapted for the purpose, it is apparent that various changes and modifications can be made in the details of construction, without departing from the spirit of my said invention. For instance, in place of the slot 14 in the tube 16, one opening or a plurality of openings might be employed, with suitable means for covering part thereof at will, to accomplish a similar result. Also, the tube 16 might be omitted, and a slot, opening, or a plurality of openings be provided in the air intake tube 8, with means for covering part of said slot, opening or openings at will, to accomplish a similar result.

While I have not explained the action of my device on the volume of oil drawn up into the mixture, it will be apparent that when a larger volume of air is admitted to the mixture, the suction on the oil tank is reduced, and the volume of oil drawn up into the mixture is reduced. Conversely, when the volume of air admitted to the mixture is reduced, the suction upon the oil tank is increased, and more oil is drawn up into the mixture.

Having thus described my invention, what I claim and desire to secure by Letters Patent is the following:

4

In an air intake for liquid feeds for furnaces, internal combustion engines and the like, an adjustable means for regulating the amount of air admitted to said feed, said adjusting means comprising a tube having linearly extending air inlet means in at least one wall, a partition in said tube beyond said air inlet means and having a central opening, a linearly slotted tube adapted to slide up and down in said partition opening whereby to permit a larger or smaller volume of air to enter said slotted tube at the air inlet side of said partition and being conveyed to the air intake tube at the other side of said partition, a closure cap linearly movable on said tube at the end adjacent the air inlet means and an actuating connection between said closure cap and said linearly slotted tube.

CHARLES M. COLVIN.
